SHEARING MECHANISM

Frederick Toop, York, Pa.

Application February 27, 1941, Serial No. 380,943

14 Claims. (Cl. 30—228)

This invention relates to mechanically operated shears for cutting sheet material.

The invention is applicable to portable machines and also to stationary machines, and is concerned with various improvements in the construction of the shears, and in the driving mechanism by which rapid strokes of small amplitude are imparted to the cutting blades.

An object of the invention is to provide an improved shearing mechanism capable of cutting curved and straight lines with equal facility, of cutting sheet metal the thickness of which is relatively large for the size of the tool and also capable of attaining a relatively high output or rate of cut in feet per minute.

Another object of the present invention is to provide an improved heavy duty shearing mechanism of marked simplicity and great durability, and adapted to stand up under the rough usage to which such tools are subjected under shop or factory working conditions.

Another object of the present invention is to provide an improved shearing mechanism having means for supporting two movable cutting blades so that both blades can be operated by rapid strokes of small amplitude.

Another object of the present invention is to provide an improved shearing mechanism in which the cutting blades are so constructed and arranged that full visibility of the work at the cutting point may be obtained irrespective of the position in which the tool is held.

Another object of the invention is to provide an improved shearing mechanism in which the connecting parts between the blades and the frame will offer a minimum of obstruction to the free movement of the machine through the metal when either straight or curved outlines are being cut.

Another object of the invention is to provide an improved shearing mechanism in which the supporting frame and the cutting blades are constructed so as to prevent bending of the work sheet during the shearing operation.

Another object of the invention is to provide an improved shearing mechanism having two simultaneously movable cutting blades mounted on a supporting frame and operable in such a manner as to produce cutting strokes which do not injure the sheared edges of the work material.

With these and other objects in view the present invention comprises the novel features of construction and combination of elements which will be hereinafter described and claimed.

In the accompanying drawings:

Fig. 1 is a perspective view looking at one side of a shearing tool embodying the present invention;

5 Fig. 2 is a perspective view looking at the other side of the tool;

Fig. 3 is a front elevation of the tool;

Fig. 4 is a bottom plan view;

Fig. 5 is a fragmentary plan of the lower cutting blade of the tool;

Fig. 6 is a vertical transverse section taken on the line 6—6 of Fig. 1;

Fig. 7 is a vertical transverse section taken on the line 7—7 of Fig. 4;

15 Fig. 8 is a vertical transverse section taken on the line 8—8 of Fig. 3;

Fig. 9 is a vertical longitudinal section showing the cutting blades in open position;

Fig. 10 is a vertical transverse section of the operating mechanism in the position shown in Fig. 9;

Fig. 11 is a sectional view similar to Fig. 9 showing the cutting blades in closed position;

Fig. 12 is a sectional view similar to Fig. 10 of the operating mechanism in the position shown in Fig. 11;

Fig. 13 is a perspective view of a piece of sheet metal having a slit cut therein;

30 Fig. 14 is an enlarged sectional view of a piece of sheet steel;

Fig. 15 is an enlarged sectional view of a piece of sheet steel showing the manner in which ordinary shearing mechanism cuts a slit therein; and

35 Fig. 16 is an enlarged sectional view of a piece of sheet steel showing the manner in which the shearing mechanism of the present invention cuts a slit therein.

Referring to the drawings, the shearing mechanism may comprise a frame or shoe 21 which 40 constitutes the base member of the tool, said frame being adapted to support the other parts of the tool and being adapted to be moved by an operator over the work bench, table, or other support to guide the cutting elements of the tool through the work.

Heretofore, in constructing mechanically operated shearing mechanisms or tools, in order to provide a tool which was portable and easily manipulated by an operator, the parts of such tools, and especially the parts constituting the supporting elements of the tools, were made of materials so light in weight that, when it was attempted to use the tools for cutting thick gauge or heavy sheet steel, the tools would not stand up 50 under such hard and severe usage. In other

words, while the tools could be used time after time for cutting thin sheet metal, when such tools were employed for the purpose of cutting thicker metal, the cutters would soon be injured to such an extent that the work produced was of inferior quality, and, therefore, not acceptable. Therefore, in order to overcome the weakness and deficiencies of the former types of shearing mechanisms, it has been necessary to design the tool in such a way that all working parts thereof function satisfactorily for their intended purpose.

It has been found that mechanically operated shearing mechanisms operate to best advantage and produce cleaner cuts when such shearing mechanisms embody two simultaneously movable cutting blades. It has also been found that the cutting blades should be so operated as to produce rapid strokes of small amplitude.

According to the present invention the base member 21 is formed of a substantial body of metal, as shown, and this member has a specific outline so as to cooperate with the other parts of the tool and thereby provide a tough cutting machine.

From the central portion of the base 21, there projects forwardly on opposite sides of the base, a pair of legs 22 and 23, the leg 23 being somewhat longer than the leg 22. The extremities of the legs 22 and 23 are spaced apart a suitable distance from each other.

The upper surface of the base member 21, and including the upper surface of both legs 22 and 23, is formed a substantially flat or plane surface. From the tip of one leg around the back of the base 21 and to the tip of the other leg, the outer periphery of the base is substantially thick, as indicated at 24. The peripheral wall 24 may be arranged substantially at right angle to the plane of the top surface of the base 21, as shown in Fig. 9. The rear portion of the wall 24 is arcuate in plan.

The inner peripheral wall 25 of the base is, at the central portion thereof, comparatively less in height than the height of the outer peripheral wall, as shown best in Fig. 9. On the other hand, the thickness of the legs 22 and 23 is substantially the same as the height of the outer peripheral wall 24, throughout the length of said legs. From the thin central portion 25 of the inner peripheral wall, the bottom surface of the base gradually thickens outwardly towards the two legs 22 and 23 and also thickens outwardly towards the outer peripheral wall 24, the construction being such that the bottom surface of the base is inclined outwardly and downwardly from the inner central portion thereof to the outer periphery thereof, as indicated at 26, Fig. 9.

The bottom surface 27 of the leg 23 is formed so as to provide a bearing surface for resting on the work bench, table or other supporting surface on which the tool is used.

The base 21 is so shaped that when the portion 27 of the leg 23 is disposed on the work bench in the position illustrated in Figs. 1 and 3, and the tool held in the normal operating position shown, the leg 22 will be disposed at a considerable distance above the level of the work bench. Since the bottom of the leg 23 is comparatively narrow in width, the amount of friction produced by the engagement of the leg with the work surface will be reduced to a minimum. Also, since the tool is so constructed that only the one leg 23 is adapted to support the tool on the work bench, the tool can be easily manipulated during operation thereof.

From the portion of the base 21 constituting the leg 22, there projects upwardly an arm 28 composed of three sections; namely, a substantially vertical section 29 which is integral with the leg 22, a horizontal section 30 which extends from the upper portion of the section 29 laterally across the front portion of the base towards the leg 23, and thirdly a section 31 which extends downwardly from the outer end of the section 30. The section 30 is disposed a suitable distance above the base 21, and the section 31 also terminates a suitable distance above the main portion of the base.

Projecting rearwardly from the portion 29 of the arm 28, is another arm 32, adapted to be rigidly connected to the housing of the power operating mechanism of the tool.

The legs 22 and 23 provide means to enable the lower cutter member 33 of the tool to be pivotally mounted in the base 21, and the arm 28 provides means to enable the upper cutter member 34 to be pivotally mounted on the base.

The lower cutter member 33 comprises an arcuate body disposed in the base, between the members 22 and 23.

At one side, the front portion of the lower cutter member 33, adjacent to the leg 22, is formed with a forwardly projecting portion 35 which is pivotally connected to the base 21 by means of a pivot pin 36 mounted in the leg 22, as shown best in Fig. 7.

The other side of the lower cutter member 33 is formed with an arm 37 which is disposed substantially in parallel relationship to the leg 23.

The arm 37 is formed with a trunnion 38 which is mounted in an opening 39 formed in the leg 23, as shown in Figs. 1 and 5.

The pivots provided by the pin 36 and the trunnion 38 are disposed at an angle to the horizontal work bench when the tool is disposed in the position shown in Fig. 3. However, such pivots are so arranged as to permit the lower cutter member to swing freely within the base 21 in the manner to be hereinafter more fully described.

The lower cutter member 33 is thus pivotally mounted at its front end to the front end of the base 21, and the portion 37 of said member 33 is formed so as to receive a blade 40.

The blade 40 is mounted in a notch or recess 41 formed in the upper surface of the arm 37, and may be detachably retained in said notch by means of a screw 42.

The inside edge of the blade 40 is inclined, as indicated at 43, Fig. 8, so as to provide a sharp cutting edge.

The lower cutter member 33 is preferably so formed with a variable contour as to provide means for separating the parts of the sheet material as it is cut by the machine and for guiding the same so that such cut material will be deformed a minimum amount during the shearing operation. Therefore, the front edge of the central portion of the lower cutter member 33 is made very thin, as indicated at 44, Fig. 9.

The upper surface of the lower cutter member 33 is substantially flat and is disposed in substantially the same plane as the plane of the upper surface of the base 21 when the cutter members 33 and 34 are in an intermediate position. On the other hand, the front edge of the lower cutter member 33 is thinnest at the zone indicated by the numeral 44 in Fig. 4, which zone is that portion of the lower cutter member 33 which is directly to the rear of the cutting edge 43 of the lower blade 40. From this thin zone

44, the thickness of the lower cutter member 33 gradually increases rearwardly and laterally towards the adjacent portions of the base 21, and at the rear of the central portion of the lower cutter member 33, the outer peripheral wall 45 thereof has a thickness equal substantially to the thickness of the adjacent inner wall portion 25 of the base 21, as shown in Fig. 9.

In this way, although there is a small gap between the portions 25 and 45 of the base 21 and the lower cutter member 33, respectively, as shown in Figs. 9 and 11, due to the manner in which the parts are constructed, the several portions of the sheet material being cut by the tool will pass unobstructedly rearwardly with respect to the base and the lower cutter member as the tool is moved forwardly through the material.

By comparing Fig. 9 with Fig. 11, it will be noted that the vertical movement which is imparted to the lower cutter member 33 with respect to the base 21 is so slight and the rapidity of this vertical movement is so fast that the sheet material is prevented from lodging against the lower curved corner 46, of the front edge of the base 21.

Projecting rearwardly from the main body of the lower cutter member 33, is an arm 47 which is operatively connected to the operating mechanism of the tool in the manner to be hereinafter described.

The upper cutter member 34 is pivotally mounted on a pin 48 carried by the sections 29 and 31 of the arm 28, as shown in Figs. 1 and 2.

The upper cutter member 34 comprises a head located in front of the pivot pin 48 and having formed in the under portion thereof, a recess 49 for the upper blade 50.

The head of the upper cutter member 34 is, as shown in Fig. 6, formed with a threaded opening 56 for the reception of a threaded sleeve 57. Disposed within the sleeve 57 is the shank of a screw 58, the head of said screw being mounted in an opening 59 formed in the blade 50. The upper portion of the sleeve 57 is formed with a hexagonal head 60 which provides means by which the sleeve may be engaged by a suitable tool, such as a wrench and disposed in the desired position in the upper cutter member 34. A nut 61 is mounted on the upper threaded extremity of the screw 58, said nut being adapted to be turned down tight against the head 60 so as to lock the screw 58 rigid with the sleeve. The recess 49 in which the blade 50 is mounted is formed with parallel side walls 62 and 63 (Figs. 1 and 4) and is open at each end. The slot thus provided for the blade 50 extends transversely across the front of the upper cutter member 34, so that the blade 50 can be shifted laterally thereof.

One end of the blade 50 is formed with a beveled cutting edge 64 and this cutting edge is adapted to be disposed in the desired relationship with respect to the cutting edge 43 of the lower blade 40. The upper blade 50 can be correctly positioned in the desired manner with respect to the lower blade 40 while the nut 61 is not securely tightened against the head 60 of the sleeve 57. However, after the blade 50 is correctly positioned, the nut 61 is adapted to be made tight with the top of the sleeve 57. A set screw 65 is mounted in the upper cutter member 34 and has a tapered lower end portion 66 adapted to engage the edge of the blade 50 opposite to the cutting edge 64 in order to prevent lateral sliding movement of the blade 50 in the

recess 49 after the blade has been properly set therein.

Projecting rearwardly from the upper cutter head 34 is an arm 67 which is operatively connected to the operating mechanism of the tool in the manner to be hereinafter described.

Since the two cutter blades 40 and 50 are adapted to operate rapidly, and since the movements of said blades are of small amplitude, the operating mechanism found most suitable for actuating the blades comprises reciprocated means operatively connected to the arms 47 and 67 and constructed in the manner to be hereinafter described and shown in Figs. 9, 10, 11 and 12.

An electric motor of any appropriate type or kind (not shown, with the exception of the front end portion of the motor shaft), is mounted within a casing having a main part 71 and an end portion 72 formed with an enlarged portion 73 to receive a housing 74 for the operating mechanism.

The end of the casing 71 opposite to the end having the portion 72 may carry a handle (not shown) as is customary in the construction of manually operated power tools.

The housing 74 is removably secured to the portion 73 by screws 78 (Fig. 10), or by any other appropriate means, and the portion 72 may be removably secured to the portion 71 by any appropriate means (not shown).

The housing 74 has a closure 80 removably secured to the front end thereof by screws 81.

The closure 80 is formed on its inner or rear side with parallel guides 82, between which are disposed two reciprocative members 83 and 84.

The parallel guides 82 engage the side edges of the members 83 and 84 and thereby prevent relative movement of these members except in a straight line, normally upward and downward or towards and from a support element or socket 85 formed in a boss 86 or extension of the housing 74.

The reciprocative member 83 is formed with an opening 87 which is made elongated transversely of the longitudinal center line of said member, as shown in Fig. 10.

An opening 88, similar in form to the opening 87 is formed in the reciprocative member 84.

The member 84 is slidably mounted on the member 83, as shown in Fig. 9, and said member 84 is formed with a socket or element 89 adapted to receive a spherical end portion 90 of the arm 67, for operation of the upper cutter member 34 as hereinafter described. The arm 67 is adapted to extend through an opening 93 formed in the closure 80.

The reciprocative member 83 is constructed somewhat longer than the reciprocative member 84 and the end of the member 83 nearest the socket 85 is formed with a lateral extension or offset portion 94.

The portion 94 is formed with a socket or element 95 adapted to receive a spherical end portion 96 of the arm 47 of the lower cutter member 33, the arm 47 extending through an opening 98 formed in the closure 80.

The member 83 is slidably mounted on a supporting member 99 preferably made integral with the portion 72 of the casing and extending from the inner portion of said casing towards the closure 80, as shown in Fig. 9.

As shown in Fig. 10, the portion 94 of the member 83 provides a broad bearing surface adapted to engage the inner face of the closure

80 to thereby constitute a sliding guide for the member 83. In other words, the member 83 is slidably mounted between the closure 80 and the supporting member 99 and is thus held from lateral shifting movement therebetween. The member 94 also has another purpose, in that it functions as means for closing the exposed portion of the opening 98 in the closure 80.

Formed on the extremity of the motor shaft 100 is a gear 101 which has teeth in meshing relationship with the teeth of a gear 102.

The gear 102 is fixed to a shaft 103, mounted at one end in a bearing 104 mounted in the casting 73, as shown in Fig. 9.

The shaft 103 extends through the openings 87 and 88 of the reciprocative members 83 and 84, respectively, and also through a bearing 105 formed in the closure 80.

A washer 97 is mounted on the shaft 103, and said washer is interposed between the reciprocative member 83 and the gear 102 so as to support the end of the member 83 opposite to the end supported by the member 99.

Formed on the shaft 103 is a pair of eccentrically positioned elements 106 and 107 adapted to move in the openings 87 and 88, respectively, of the reciprocative members 83 and 84.

In order to prevent undue wear of the eccentrics 106 and 107, said eccentrics are fitted with bushings 108 and 109, respectively, said bushings being preferably arranged concentric of said eccentrics, as shown in Figs. 9 and 10.

The eccentrics 106 and 107 are diametrically disposed with respect to the longitudinal center line of the shaft 103, the eccentric 106 extending laterally in one direction from the center of said shaft and the eccentric 107 extending laterally from the center of the shaft in the direction opposite to said eccentric 106. Both eccentrics and their respective bushings are circular in outline and the maximum diameter of the bushings is substantially equal to the minimum width of the openings 87 and 88, as shown in Fig. 10.

The contours of the openings 87 and 88 and the arrangement of the eccentrics 106 and 107 are such that the reciprocative members 23 and 24, which are disposed between the guides 22, move in a straight line across the axis of the shaft 103.

The outer end of the arm 32 is mounted in the socket 85, heretofore referred to, the end of the arm and the socket being so formed that the base 21 is made rigid with the housing of the operating mechanism.

In order to detachably connect the shearing tool to the power device, the portion 110 of the arm 32 is formed with a transverse slot or groove 111 adapted to receive the shank 112 of a spring-pressed locking-pin 113.

The locking-pin 113 is mounted in the boss 86 and arranged transversely of the device so as to extend across a portion of the socket 85, as shown in Fig. 10.

In order to permit the insertion of the end 110 into the socket 85 and the withdrawal of the arm 32 from said socket without the necessity of removing the locking-pin 113 from the device, said pin has a notch 114 formed in the portion of its shank 112 which normally extends across the socket opening 85. The contour of the notch 114 is such that when the pin 113 is turned to the position shown in Fig. 10, the full area of the socket opening 85 will be provided for the insertion and the withdrawal of the arm portion 110. After the arm is mounted in the socket 85, as

shown in Fig. 9, the pin 113 is adapted to be rotated to the position in which the notch 114 is moved out of registration with the opening of the socket 85. In such position, the main shank 5 portion 112 of the pin 113 will be disposed in the groove 111, thereby preventing movement of the arm 32 relative to the housing 74. In this way the tool will be rigidly connected to the power mechanism housing.

The pin 113 is held in either of the two positions referred to above by a coil spring 115 mounted in a recess 116 and encircling an end of the pin, said spring bearing at one end against a shoulder 117 and at the other end against a washer or disk 118 mounted on the extremity of said pin. The action of the spring 115 normally retains the operating head 119 of the pin 113 in engagement with a shoulder 120. The head 119 is formed with a lug 121 adapted to engage the shoulder 120 when the pin 113 is in the position shown in Fig. 9.

The disposition of the eccentrics 106 and 107 with respect to the axis of rotation of the shaft 103 and the manner in which said eccentrics 25 are arranged in the reciprocative members 83 and 84, respectively, is such that said members will be moved simultaneously in opposite directions when the shaft 103 is rotated. The reciprocating movements of the members 83 and 84 30 in opposite directions imparts a similar movement to the arms 47 and 67, so that said arms will be alternately moved toward and away from each other. In this way the cutting elements or blades 40 and 50 will be operated to produce 35 the desired shearing action.

By providing means, such as the element 85, for retaining the tool rigid with the motor casing, and by providing means, such as the reciprocative members 83 and 84, for simultaneously 40 operating the tool arms 47 and 67, the shock which occurs at the end of each reciprocative movement of the tool arms is neutralized, with the result that the tool operates more smoothly than when a single reciprocative or cutting element is employed.

It will be understood that in the case of a cutting tool having a single reciprocative member operated at considerable speed, first in one direction, and then in the opposite direction, the 50 suddenness which the single reciprocative member changes its direction of movement, causes a pronounced shock in the mechanism. On the other hand, since both of the reciprocative members 83 and 84 reverse their direction of movement simultaneously, the shock at one end balances the shock at the opposite end resulting from the change in direction of movement, so that little or no vibration or shock is produced in the operating mechanism and the mechanism 55 operated thereby. Thus, the simultaneous double reciprocative action in opposite directions of the members 83 and 84 produces a mechanical movement simulating somewhat the smooth motion produced by a balanced wheel.

60 For instance, after the members 83 and 84 have attained their normal operating speed, the reciprocative movements of said members continue for a considerable length of time after the current supplied to the driving motor has been cut off. That is to say, the arms 47 and 67 are actuated approximately three times longer by the present operating mechanism than is the case where a single reciprocative member is employed. Another feature of the present operating mechanism is that the double action of the

two members 83 and 84 is obtained by the use of a single operating shaft and gear drive therefor.

The amount of reciprocatory motion imparted to the members 83 and 84 by the shaft 103 can be observed by comparing the position of the parts shown in Figs. 9 and 10, with the position of the same parts in Figs. 11 and 12, respectively. Since the length of the arms 47 and 67 from the respective pivots of the lower cutter member and the upper cutter member to the points at which said arms are mounted in the reciprocative members 83 and 84, respectively, is considerably greater than the distance from said pivots to the point at which the cutting edge of the blade 40 engages the cutting edge of the blade 50, the comparatively short reciprocating movements of the members 83 and 84 which are transmitted by the arms 47 and 67 to the blades 40 and 50, respectively, result in the blades being operated very rapidly with small amplitude. Thus the shearing action produced by the mechanism of the present invention comprises a multiplicity of very short cuts.

It is well known that sheet metal as formed in the steel mill has a very thin skin on each of its exposed surfaces. This skin provides a tough layer which the cutting edges of shearing mechanism must first penetrate when the sheet metal is being cut up. During the shearing operation, after the shears have penetrated the skin on the surface of the sheet metal, the central portion of the sheet metal offers little resistance to the cutting action of the shears, with the result that the cutting edges of the shears pass through the central portion of sheet metal more readily than the cutting edges pass through the upper and lower layers of skin of the sheet metal.

In the drawings, Fig. 14 shows an enlarged sectional view of a piece of ordinary sheet metal, such as sheet steel, which is designated generally by the reference numeral 122. The sheet of metal 122 has an upper skin surface 123, a bottom skin surface 124, and a central portion 125.

When shears having a shingle movable cutter are used for making a cut in the sheet metal 122, the action of the single cutter element in passing through the sheet metal produces ragged edges at the cut. These ragged edges are caused by the action of the cutter element as shown in Fig. 15, wherein it will be noted that, during downward movement of the cutter the tough upper skin 123 of the sheet metal is bent downwardly into the central portion of the sheet metal and the body of metal constituting the central portion is forced downwardly thereby forcing the cut edge portion of the lower skin 124 downwardly so as to produce the ragged edges above referred to.

It will be understood that the amount of cutting action produced by each stroke of the cutter blade of any shearing mechanism determines the magnitude of the ragged or rough cut edges formed on a cut piece of sheet metal. The magnitude of the rough edges depends on the length of each stroke. If the strokes of the cutters are very short, then the ragged edges will not be as noticeable or pronounced as when the strokes of the cutters are relatively long.

By the present invention it has been the purpose to eliminate, as far as possible, ragged edges along the cut parts of sheet metal. Thus, as shown in Fig. 16, due to the manner in which the blades 40 and 50 are operated simultaneously, as the cutting edges of said blades move simultaneously through the sheet of metal from both

sides thereof, both cutters, as they pass through the skins 123 and 124, turn or bend the skins towards the center of the sheet of metal, as indicated at 126. In this way there is no way for a ragged edge to be formed along the portion of sheet metal cut by the present tool, due to the manner in which the cutters 40 and 50 are arranged and to the manner in which they operate.

As shown in Fig. 13, the shearing mechanism of the present invention is so constructed that when a cut 128 is made in a piece of sheet metal 129 the metal is not bent or otherwise distorted at the point 130 of the cut. In other words, the action of the two cutter members 40 and 50, as well as the construction of the base 21, is such that the natural tendency of the sheet metal to flex or bend is not destroyed. Consequently the rapid cutting strokes of the cutters 40 and 50 of slight amplitude, produces a clean cut in the sheet metal and the edges of the cut portions of the sheet metal will be smooth, as shown in Fig. 13.

In cutting thin metal, that is to say, sheet metal not exceeding twenty-two gauge, there is very little resistance offered by the metal. On the other hand, when a shearing machine is used for cutting heavier metal, that is to say, sheet metal having a thickness exceeding approximately twenty-two gauge, there is a greater resistance offered, and the resistance becomes greater as the thickness of the metal increases. Therefore, it has been found necessary to provide a portable power actuated shearing mechanism that will eliminate the resistance by opening up the metal in a progressive manner to permit the cutters to readily follow through with a minimum amount of manual force on the part of the operator. These results are obtained without in any way bending or distorting the metal during the cutting operation. The only way in which these results can be obtained is by the use of the double cutters that are operated simultaneously in the manner heretofore described. In other words, it is necessary to mount the lower cutter member 33 in the base 21 in the manner herein shown and described in order to obtain the above referred to results. The lower cutter not only cuts the bottom skin of the sheet metal, but it directs the bottom section of the cut metal under the cutter and thereby opens up the metal to permit the follow through. This action is obtained by the construction provided by the front or leading edge of the lower cutter member 33 from the point indicated at 44, Fig. 4, to the thickened portion 35. Referring now to Fig. 9, as the shearing mechanism moves forwardly through the metal, the rear portion of the lower cutter member 33 moves downwardly as the blade 40 moves upwardly during the cutting operation and in doing so forces the metal thereunder downwardly. At the same time the metal being cut is given a setting point at the front edges of the cutting blades. At the instant the metal is given the setting point at the front of the blades, the rear portion of the cutter member 33 holds the metal down, thereby eliminating any tendency for the metal which has been cut to rebound. By this action of the lower cutter member 33 the metal is opened sufficiently to permit the machine to follow through its work with a minimum amount of resistance. It will also be noted that this action is obtained without causing any distortion of the metal as it is cut.

As shown in Fig. 3, during normal cutting operation the lower cutter member 33 is disposed

in an elevated position above the plane of the work table or other support on which the leg 23 rests during the cutting operation. With the lower cutter member 33 thus disposed in an elevated position above the top of the work table, free movement is permitted of all operating parts of the mechanism, as will be understood. In this way, the tool can be moved smoothly over the work table without the oscillating movements of the cutters being transmitted to the main base or shoe 21.

Due to the manner in which the lower cutter member 33 is pivotally mounted in the legs 22 and 23 by the pivots 36 and 38, respectively, the lower cutter member 33 can be formed with the thin front edge 44 without affecting the strength or stability of said cutter member. Thus, it will be noted, that by the provision of the two large pivots 36 and 38, which pivots are arranged at opposite sides at the front of the lower cutter member 33, the intermediate portion of said cutter member can be so shaped as to provide the thin leading or entrance edge 44, without reducing or otherwise impairing the strength of said cutter member. Should supporting means be used other than the type of supporting means provided by the pivots 36 and 38, the whole body of the lower cutter member 33 would have to be made much thicker and heavier so as to prevent said member from breaking during operation of the machine. The thin leading edge 44 permits the machine to move forwardly through the metal with little resistance.

Having thus described my invention, what I claim is:

1. A portable shears comprising a base member, a pair of movable cutting blades pivotally mounted in said base member, said cutting blades being superposed with respect to each other and the pivots for said cutting blades being superposed with respect to each other, and means for imparting rapid movements to said cutting blades in opposite directions so that said blades will have shearing movements past the edges thereof of small amplitude.

2. A mechanically operated shearing mechanism comprising a base member adapted to be manually moved through the material being cut, a pair of movable cutter blades pivotally mounted in said base member, the pivot for the upper cutter blade being superposed in spaced relation with respect to the pivot of the lower cutter blade, and means for simultaneously operating said cutter blades so that said blades will have shearing movements of small amplitude.

3. In a motor operated shearing mechanism, a base member rigidly connected to the housing of the motor, a pair of cutter blades pivotally mounted in the base for shearing movement, each blade having its own pivot, an arm projecting from each blade, and means operated by said motor and operatively connected to said arms for simultaneously operating said blades so that the blades will have shearing movements past the edges thereof of small amplitude.

4. In a motor operated shearing mechanism, a base member rigidly connected to the housing of the motor, a pair of cutter blade elements pivotally mounted in the base for shearing movement, an arm projecting from each blade element, a pair of members mounted in said motor housing for reciprocative strokes, each reciprocative member having an opening therein, a shaft operatively connected with the motor shaft and having two eccentrics thereon mounted respec-

tively within the openings of said reciprocative members, said eccentrics being located diametrically opposite each other with respect to the longitudinal center line of said eccentric shaft so that said members will be reciprocated simultaneously in opposite directions, and means for operatively connecting the extremity of said blade element arm to one of said reciprocative members and for operatively connecting the extremity of the other said blade element arm to the other reciprocative member, so that said cutter blades will be operated by said reciprocative members.

5. In a motor operated shearing mechanism, a base member rigidly connected to the housing of the motor, a pair of cutter blade elements pivotally mounted in the base, the pivot for the upper cutter blade being superposed in spaced relation with respect to the pivot of the lower cutter blade, an arm projecting from each blade element, a pair of members mounted in said motor housing for reciprocative strokes, each reciprocative member having an opening therein for receiving the end portion of each of said cutter blade element arm respectively, and means operatively connecting said reciprocative members with the shaft of said motor for reciprocating said reciprocative members simultaneously in opposite directions.

30. 6. In a motor operated shearing mechanism, a base member rigidly connected to the housing of the motor, a pair of cutter blade elements pivotally mounted in the base, the pivot for the upper blade element being superposed in spaced relation with respect to the pivot of the lower blade element, an arm projecting from each blade element, a pair of members mounted in said motor housing for reciprocative strokes, each reciprocative member having an opening therein,

35 40. 45. 50. 55. 60. 65. 70. 75. a shaft operatively connected with the motor shaft and having two eccentrics thereon mounted respectively within the openings of said reciprocative members, said eccentrics being located diametrically opposite each other with respect to the longitudinal center line of said eccentric shaft so that said members will be reciprocated simultaneously in opposite directions, and means for operatively connecting the extremity of said blade element arm to one of said reciprocative members and for operatively connecting the extremity of the other said blade element arm to the other reciprocative member, so that said cutter blades will be operated by said reciprocative members.

7. In a motor operated portable hand shear, a base member rigidly connected to the housing of the motor and having a pair of legs projecting forwardly therefrom and an arm of substantially inverted U-shape projecting upwardly therefrom, a lower cutter member pivotally mounted in the legs of said base and having a blade carrying portion arranged in substantially parallel relationship to one of said legs, a blade mounted in said portion and having a cutting edge disposed on the side of said portion inwardly with respect to said leg, an upper cutter member pivotally mounted in said inverted U-shaped arm and having a blade carrying portion arranged above the forward end of said lower cutter member, a blade mounted in said upper blade carrying portion and having a cutting edge disposed at the side of said upper blade carrying portion to cooperate with the cutting edge of said lower blade to shear the material, arms projecting rearwardly from both of said

cutter members, respectively, and means operated by said motor and operatively connected to the extremities of said cutter member arms for simultaneously operating said blades in opposite directions.

8. In a motor operated portable hand shear, a base member rigidly connected to the housing of the motor, a lower cutter member pivotally mounted in said base, an upper cutter member disposed in spaced relation above said lower cutter member and mounted in said base by a separate pivot, cutter blades carried by both of said cutter members and arranged to shear the material, and means operated by said motor and operatively connected to both of said cutter members for simultaneously operating said blades in opposite directions to produce rapid cutting strokes of small amplitude.

9. In a motor operated portable hand shear, a base member rigidly connected to the housing of the motor and having an arcuate central portion and a pair of legs projecting forwardly therefrom, a lower cutter member pivotally mounted in said base member and arranged between the legs thereof, an upper cutter member pivotally mounted on said base and arranged in spaced relation above said lower cutter member, and means operated by said motor and operatively connected to both of said cutter members for operating said cutter members to reciprocate the cutters simultaneously in opposite directions with respect to said base member.

10. In a motor operated shearing mechanism, a base member rigidly connected to the housing of the motor, a pair of cutter blade elements pivotally mounted in the base, the pivot for the upper blade element being superposed in spaced relation with respect to the pivot of the lower blade element, an arm projecting from each blade element, a separate actuating member for each said cutter blade element, each actuating member having means for operatively connecting the arm of a cutter blade element thereto, and power transmitting means operatively connected to each of said actuating members and to the shaft of said motor so as to effect simultaneous reciprocative movements of said actuating members in opposite directions to thereby effect operation of said cutter blades by the operation of said motor.

11. In a power operated shearing mechanism, a base member having a pair of legs projecting forwardly therefrom, a lower cutter member pivotally mounted in the legs of said base member and having a blade carrying portion arranged adjacent to one of said legs, said lower cutter member having its body extending from said blade carrying portion formed with a narrow front edge, a substantially flat top surface and a bottom surface of irregular contour of gradually increasing thickness away from said blade carrying portion, an upper blade carrying portion projecting upwardly from said base member, an upper blade carrying element pivotally mounted in said upwardly projecting portion of said base member and having a cutter blade mounted therein for cooperating with the lower cutter blade, the central portion of said base extending rearwardly from said legs and having a substantially flat top surface and a bottom surface of irregular contour of gradually increasing thickness rearwardly from the front edge of the

base towards the rear edge thereof, the front edge portion of said base having a thickness at the central part thereof corresponding substantially to the thickness of the rear central portion of the lower cutter member, so that when the device is in operation the parts of the material which are cut are separated only sufficiently to prevent deformation thereof a minimum amount and are guided unobstructedly towards the rear of the device, and means operatively connected to each of said cutter members for simultaneously moving the same in opposite directions of small amplitude.

12. In a power operated shearing mechanism, a base member having a pair of legs projecting forwardly therefrom, the central portion of said base extending rearwardly from said legs and having an arcuate front edge and an arcuate rear edge thicker than said front edge, a lower cutter member pivotally mounted in the legs of said base and having a blade carrying portion arranged adjacent to one of said legs, a blade mounted in said blade carrying portion in front of the pivots, said lower cutter member having a narrow front edge between said pivots and a main body portion of gradually increasing thickness extending rearwardly from the front edge and adapted to force the cut metal which passes under the lower cutter member downwardly below the front edge of said base during operation of the shearing mechanism, an upper blade carrying element pivotally mounted in said base above said lower cutter member and having a cutter blade mounted therein for cooperating with the lower cutter blade, and means for operating both cutters simultaneously in opposite directions.

13. In a power operated shearing mechanism, a base member having a pair of legs projecting forwardly therefrom, a lower cutter member pivotally mounted in the legs of said base member and having a blade carrying portion arranged adjacent to one of said legs, a cutter blade mounted in said blade carrying portion in front of said pivots, an upper blade carrying element pivotally mounted in said base by a pivot arranged in spaced relation above the pivots of said lower cutter member, said upper blade carrying element having a cutter blade mounted therein in front of its pivot for cooperating with the lower cutter blade, said lower cutter member being arranged with respect to said base member so as to direct the cut metal which passes thereunder during the shearing operation downwardly beneath the bottom of the base member without deforming the metal, and means operatively connected to both cutters for simultaneously operating the same in opposite directions.

14. A power operated shearing mechanism comprising a base member adapted to be moved through the material being cut, a pair of movable cutter blades pivotally mounted in the base member, said cutter blades being superposed with respect to each other and the pivots for said blades being superposed with respect to each other so that when the blades are moved about their pivots the blades will have a shearing movement past the edges thereof, and means for simultaneously operating said blades to cause the blades to move in opposite directions about their respective pivots.

FREDERICK TOOP.
